UNITED STATES PATENT OFFICE

ANDREAN G. RONNING, OF MINNEAPOLIS, MINNESOTA; JACOB A. RONNING AND
ADOLPH RONNING, EXECUTORS OF SAID ANDREAN G. RONNING, DECEASED

SPHYGMOGRAPH

Application filed July 29, 1927. Serial No. 209,365.

This invention relates to devices known as sphygmographs or sphygmometers for permanently recording the variables and characteristics of human (or animal) heart beats, and the primary object is to provide means, of a simple, efficient and practical nature, for graphically indicating the heart beats in such a manner that a complete and accurate record of the frequency, strength, regularity and consistency of the heart action may be obtained. The value of such a record is obvious, as it enables the person or a physician to carefully and deliberately examine the heart action at such times as may be convenient, and permits a closer and more valuable observation of the heart than is obtainable, for instance, by merely timing the pulse, to a watch, a practice which is not only unreliable and inaccurate, but at its best indicates nothing more than the heart beat frequency. The present device, however, will not only positively and accurately register the pulse frequency, i. e., the number of beats per minute, but will also indicate the strength of the beat, i. e., the force of the blood flow causing the arterial throbbing, and will also chart the regularity or consistency of the pulse so as to show whether or not the heart functions the same continually or if it is subject to variable periods of increased and decreased activity. Some of these characteristics can be noticed, by an expert, relying upon the sensitiveness of his finger tips to the pulse activity of the wrist. The reliability of such an observation is of course doubtful at any time, but even this is not obtainable, under ordinary circumstances, unless the expert, whether doctor or nurse, is present. The present device, on the other hand, can be used by the patient himself if necessary, and if applied by either the patient or a nurse at given intervals throughout the day, it will produce a record of the heart action that will be invaluable to the attending physician when he calls upon the patient.

In the accompanying drawings:

Fig. 1 is an enlarged elevation of the device, as seen from the left in Fig 2, but with the cover plate removed.

Fig. 2 is a side elevation, as seen from the

right in Fig. 1, of the interior mechanism, but showing the outer casing in central, vertical section.

Referring to the drawings more particularly and by reference characters, 3 designates a cylindrical casing having end doors 4 and 5, which are preferably hinged as at 6, so that the doors or covers can be conveniently opened when access to the mechanisms is desired. The casing 3 is further provided with an integral centrally depending leg 7, and a pair of laterally spaced brackets or legs 8 and 9 at the sides of the leg 7. The legs 8 and 9 have socket members 10 for receiving the middle sections of two adjacent fingers of the hand, and straps 11 for firmly securing such finger sections in the sockets. It will be understood that when the fingers are in place they will be bent at right angles, and the finger tips will extend down below the sockets to positions on either side of and below the end of the central bar 7. Thus the device is supported or carried by the hand of the operator and when it is to be used, it is so held that these two finger tips may be employed to locate the most suitable area of the body surface before the mechanism is started. The leg 7 has a bar 12 slideable therein which transmits the vibrations or pulsations into the recording mechanism. This bar has a head 13 for contacting engagement with the body surface and is normally held down by a spring 14, which yields to the pulsations. There are various spots on the body that are suitable for this purpose, but the most effective location is at the wrist, where the radial arteries are close to the surface and respond readily to the ventricular contractions of the heart, which produce the distentions in the radial arteries, and which, in turn, impart the desired fluctuations or vibrations to the rod or bar 12.

The bar 12, in addition to guiding in the leg 7, guides in a bearing extension 15 of a frame or post 16, which, in turn is integral with and extends centrally up into the casing 3. This bar 12 operates an indicator or marker 18 and an escapement mechanism, which, as a unit is designated by the numeral 19. The marker 18 is carried by the rod

12, and is spring held, as by a spring 22, against a book or series of diagram disks or sheets 20, which are rotated, in a manner to be described, and which, as they rotate, receive an irregular line of marks or impressions 21. A second spring 23, has a similar function and also serves to restore the marker to its original or lower position. The escapement 19 comprises a vertically 10 slidable rack bar 24 having a shaft 25 on which is trunnioned an anchor 26 having pulleys 27, 28 which are operatively associated with a large escapement wheel 29. An arm 30 of the anchor 26 engages and is operated by the bar 12, so that for each pulsation imparted to the head 13, the escapement 19 will permit the wheel 29 (which is spring rotated), to turn the distance between two of its teeth. Springs, such as 31, may be 20 employed to yieldingly hold the escapement bar in its operative position.

The escapement wheel 29, together with a spring case 33, which is secured to it, are rotatably carried on a shaft 34. The shaft 34 25 is journaled, at one end, in a spider like frame 35, fixed in the casing 3, and has its other end terminating and journaled in a two ended hub 36-37 of the frame 16. A spiral spring 38 is contained within the case 33 and has one 30 end secured thereto and the other end to the shaft 34, in a conventional manner, so that when the shaft 34 is turned it will wind up the spring. The shaft 34 is preferably wound by a wing nut 39 which is secured on one end 35 thereof. The shaft is held against reverse rotation by a pawl 40 and a ratchet wheel 41. When the device is not running or operating the wheel 29 is held against rotation by a tooth clutch hub 42 of a disk plate 43 which is 40 splined onto the hub member 36. The hub 42 co-operates with a similar toothed clutch hub 44 of the wheel 29. The clutch 42, 44 is closed or moved into engagement by a pin 45, which is slidably carried in the frame 16, 45 and which is actuated, against the resistance of a spring 46, by a cam or wedge member 47 carried on a second escapement wheel 48. This closing movement of the clutch, which stops all rotation of the wheel 29, also causes 50 the disk plate 43 to actuate a lever 49, throwing the upper end thereof inward or toward the disk book 20. The upper end of the lever carries a perforator or marker 50, which is thus brought into engagement with and 55 marks the face of the inner disk. Such a mark indicates the start and end of the operating cycle, and, as will soon be described, provides the means for recording the frequency of the heart beats. The lever 49, 60 which is pivotally carried by the wheel 29, as at 51, is held in its inoperative position, during the recording cycle, by suitable means, such as a spring 52, which also disengages the clutch hub 42 when the pin 45 is free from the 65 action of the cam 47. The pointer or marker

50 has a square shank 53, which is normally and non-rotatably at rest in a square socket 54 at the upper end of the lever 49. The shank is so held in the socket by a spring 55, which surrounds a reduced and round portion 56 of the shank. This spring 55, while yieldingly permitting the square portion of the shank to be withdrawn from the socket, also has a twisting action on the shank, so that when the shank is withdrawn and turned 70 in one direction the spring will have a tendency to reverse the rotation and pull the shank back to its initial position. The object of the construction 53-56 is to permit the marker 50 to pass the lower end of the frame 16 when the wheel 29 is rotated. Thus, as the wheel is about to complete a half revolution from the position shown in the drawing, rear end projection or finger 57 75 engages a cam bracket 58, secured in the lower part of the casing 3, and thus slides the squared shank 53 from the socket 54, and as the wheel continues to turn the long end of the pointer stops against the frame post 16, causing it to swing behind, but as soon as 80 the marker is clear of the post, the spring 55 will restore the parts to the initial position, as shown.

The escapement wheel 48 is secured to and rotates with a spring case 59, which, in turn, is secured on a shaft 60, rotatably carried in the hub member 37. The spring 61, within the case 59, is also of the spiral type, and has its outer end secured to the case while its inner end is anchored to a projection 62 of 100 the hub 37. The outer end of the shaft 60 is threaded to receive a wing nut 63, which may serve the double purpose of clamping the chart disks 20 in a solid book, and of winding up the spring 61. A plate 64 is 105 preferably interposed between the nut 63 and the book 20, so as to give rigidity to the charts and to serve as an effective clamping member in conjunction with the case 59. The charts themselves may be of any desired material, but are preferably made of fairly heavy 110 paper, and each is provided, adjacent to its edge, with an annular series of equally spaced members, as shown at 65 in Fig. 1. Immediately within the circle of figures 65, I print 115 two lines 66, which define the space within which the pulse is to be recorded. It may here be noted that the shaft 60 carries a ratchet wheel 67, which operates against a dog 68, on the hub 37, and thus permits rotation of the members 48, 59, 20, 64 in one direction only.

It is necessary to have the disks 20 rotate at a certain predetermined speed, preferably one revolution per minute, and this is accomplished by a time controlled escapement mechanism, generally designated by the numeral 69. This escapement consists of a shaft 70, carried in a rack bar 71, a balance wheel 72, rotatable on the shaft and having 120

5 a pinion 73 engaging a toothed segmental rack 74 of a shaft 75 journaled in a bracket 76 carried on the shaft 70. The shaft 75 is further provided with an escapement lever 77, having pulleys 78 for oscillating, intermittent engagement with the teeth of the wheel 48. The fly wheel 72 is provided with a hair spring 79, and governs the speed of the wheel 48 in the same conventional manner as 10 in a watch or clock movement.

10 The rack bar 71 is slidably mounted in bearings 80, on the post 16, and, at its lower end, extends through the casing 3, terminating in a button 81, and intermediate the button 81 and the casing is a spring 82 which tends to hold the bar 71 down, with the escapement 69 in its operative position with respect to the wheel 48.

15 The rack bar 71 has a toothed section, which engages one side of a fixed pinion 83, while at the other side the pinion is engaged by a similar section of the rack bar 24, which is also slidably, vertically, and carries the escapement 19. It will thus be seen that the 20 wheels 29 and 48 may readily be released from the respective escapements 19 and 69 by merely pushing the button 81 upwardly. To prevent the spinning or unwinding of the wheels 29 and 48, however, and to stop them 25 at a convenient starting point, for the next pulse test, I provide them with a pair of lugs 84 and 85, respectively, which stop against the ends of a cross bar 86, which is vertically movable, so that the lugs 84—85 can be released, and is carried on a rod 87 which extends down through the leg 7 to a point immediately above the button 13. This rod 87 is normally held down by a spring 88, but may easily be moved up, so as to free the 30 lugs 84, 85, and thus start the recording process, by a little extra upper pressure on the button 13.

35 With the various parts of the device in the positions shown in Fig. 1, and with the casing mounted on two fingers, as previously described, the recording process is effected as follows: After the desired arterial location is found, and the button 13 placed upon it, the device is pressed down until the rod 87 40 trips the lugs 84 and 85. The pressure is then relieved to the required extent so that the rod 12 will be made sensitive to the pulse action. The charts 20 immediately start to rotate at a predetermined speed, it being understood that the springs 38 and 61 have first 45 been wound up, and as the clutch members 42 and 44 are not closed, the wheel 29 is also free to rotate as fast as the escapement 19 will permit. As the speed of rotation of the 50 wheel 29 is dependent entirely upon the frequency of the heart beats, whereas, the speed of the charts is time controlled, it will be seen that the speed of one may be faster or slower than the other. Consequently the location 55 of the needle or marker 50, at the end of the

cycle or complete rotation of the charts, will be governed entirely by the number of heart beats per minute. And if the marker 50 is, when started, at "1" (of the figures 65) it will, at the end of the cycle, be opposite the 70 number which would indicate the number of heart beats recorded during the minute. As the minute test is terminated the cam 47 engages the rod 45, thus closing the clutch 42 and stopping the wheel 29. This same movement, acting through the lever 49, also causes the marker 50 to be brought into engagement with the face of the chart. If the marker is a pen or pencil a mark will result, or if a 75 needle, a perforation will be made adjacent 80 to the number, and thus give a permanent record of the pulse frequency.

85 During the course of the revolution, just noted, the marker 18 has also been functioning, and has imprinted or impressed the chart with an irregular saw tooth, line 21, or rather with a continuous series of short lines, each two of which have been recorded in response to the pulse beats. The length and condition, as well as the relative closeness of the 90 lines to each other, indicate various pulse characteristics. Thus, long lines would indicate a heavy or strong heart action, while shorter lines would indicate a weaker (though not necessarily slower) heart action. 95 And possibly a lower blood pressure. The angle of the pulse line (i. e. the up line as distinguished from the return stroke) with respect to the radial line of the chart would indicate the intensity or acuteness of the 100 heart action. And if some of the lines are closer than others, there would be furnished a reliable record that the heart is more or less spasmodic in its action and functions faster at certain intervals during the minute 105 test. Thus it will be seen that all of the essential characteristics of the heart action are permanently recorded, and the value of such a record, to a physician, skilled in reading it, 110 becomes inestimable.

115 When the wheel 48 has made one complete minute revolution, the lug 85 stops against the bar 86 and the recording process ceases. The graphed or marked chart is then removed, leaving the next one in position for the next test. The button 81 is then pushed up, freeing the escapement 19, thus permitting the wheel 29 to rotate with the marker 50 to its initial position, where it is stopped by the lug 84 meeting the cross bar 86. 120 Similarly the escapement 69 is freed from the wheel 48 so that if the latter has not completed its full revolution it may then do so.

125 It is understood that suitable modifications may be made in the general design and structural details of the invention as herein shown, provided, however, that said modifications come within the spirit and scope of the appended claims. Having now therefore fully shown and described my invention,

tion, what I claim to be new and desire to protect by Letters Patent is:

- 5 1. A sphygmograph comprising a circular chart having a progressive series of numbers adjacent its outer edge, a marker movable in a path adjacent to said series of numbers, but normally out of contact with the chart, time controlled means for rotating the chart with respect to the marker, an exposed 10 vibrator for contact with the body surface so as to be sensitive to arterial distentions, and means, responsive associated with the vibrator, for causing the marker to engage the chart, at a predetermined time interval, 15 whereby a mark will be described upon the chart adjacent to a number of the series which will correspond to the pulse frequency.
2. A sphygmograph comprising a housing, a recording mechanism within the housing, a 20 vibrator rod extending from the housing with its inner end operatively associated with the recording mechanism and with its outer end adapted to be applied to a body surface for responsive action to arterial distentions, and 25 means for securing the sphygmograph to two fingers of an operator's hand whereby the outer end of the vibrator rod will be positioned between the tips of the fingers so secured.
- 30 3. A sphygmograph comprising a housing, a recording mechanism within the housing, a vibrator rod extending from the housing with its inner end operatively associated with the recording mechanism and with its outer end 35 adapted to be applied to a body surface for responsive action to arterial distentions, and a pair of clamping devices, arranged at opposite sides of the vibrator rod for engagement with two fingers of the operator's hand.
- 40 4. A sphygmograph comprising a recording mechanism having a vibrator rod extending therefrom for application to the body surface so as to be responsive to arterial distentions, and which will transmit vibrations 45 thus imparted to it to the recording mechanism, said recording mechanism being spring operated but normally inactive, and means rendered operative by an inward movement 50 of the rod that is greater than that to which it is subject when normally transmitting impulses, to release the recording mechanism from its inactive condition.
- 55 5. A sphygmograph comprising a rotatable chart having an annular series of numbers thereon, means for rotating the chart at a predetermined speed, a vibrator mounted for sliding action in a radial direction with respect to the chart and having its outer end 60 exposed for body contact, a marker carried by the inner end of the vibrator for constant marking contact with the chart, and a second marker mounted for rotation on an axis coincident with that of the chart for intermittent marking contact with the chart, and

in reading conjunction with said series of numbers.

- 6 6. A sphygmograph comprising a rotatable chart having an annular series of numbers thereon, means for rotating the chart at 70 a predetermined speed, a vibrator mounted for sliding action in a radial direction with respect to the chart and having its outer end exposed for body contact, a marker carried by the inner end of the vibrator for constant 75 marking contact with the chart, and a second marker mounted for rotation on an axis coincident with that of the chart for intermittent marking contact with the chart, means for rotating the second marker, and an escapement mechanism controlled by the vibrator, for controlling the rotary movement of the second marker.

7. A sphygmograph comprising a circular chart, means for rotating the chart at a predetermined speed, a vibrator having a marker for contact with the chart as the latter rotates, a second marker, normally out of engagement with the chart, but rotatable on an axis concentric with that of the chart, means 85 for rotating the second marker, means associated with the vibrator for controlling the speed of the second marker, and means operative upon a predetermined movement of the chart for moving the second marker into 90 marking engagement with the chart.

In testimony whereof I affix my signature.
ANDREAN G. RONNING.
